UNITED STATES PATENT OFFICE.

CHARLES DWEIGHT McCALL, OF ATLANTA, GEORGIA.

HOPPER FOR HEATING PIPES.

Application filed June 15, 1922. Serial No. 568,474.

To all whom it may concern:

Be it known that I, CHARLES DWEIGHT McCALL, a citizen of the United States, and a resident of Atlanta, in the county of Fulton and State of Georgia, have invented certain new and useful Improvements in Hoppers for Heating Pipes, of which the following is a specification.

My invention relates to improvements in 10 heating and ventilating systems, and it consists in the constructions and combinations herein described and claimed.

An object of the invention is to provide a 15 hopper in the nature of a catch-all to be applied to heating and ventilating pipes in such a manner as to catch such dirt and other matter as may fall into the pipes through the floor grating.

A further object of the invention is to 20 provide a hopper of such a style as can be readily attached to existing heating and ventilating pipes without the necessity of even taking such pipes down for the purpose of installation.

25 A further object of the invention is to provide a hopper with an outlet door which is capable of being opened and closed from the floor above so as not to make it necessary to go into the basement to accomplish this 30 purpose.

Another object of the invention is to design the hopper in such a manner that all material collected thereby will gravitate toward the bottom whence it may be removed 35 through a door at the side.

Other objects and advantages will appear in the following specification, reference being had to the accompanying drawing, in which:

40 Fig. 1 is a side elevation of a portion of a hot air pipe illustrating the application of the catch-all or hopper,

Fig. 2 is a longitudinal section of the pipe and hopper shown in Fig. 1,

45 Fig. 3 is a detail front elevation illustrating the arrangement of the outlet door,

Fig. 4 is a detail section of the lower end of the hopper (similar to Fig. 2) showing the construction on a slightly larger scale,

50 Fig. 5 is a section taken substantially on the line 5—5 of Fig. 2, showing the shape of the hopper which compels the material to gravitate toward the bottom,

Fig. 6 is a detail elevation showing a floor

plate which is used when a chain pull is employed in connection with the door, and

Fig. 7 is a detail section illustrating the arrangement of the floor plate.

The purpose of the invention is to provide a hopper or catch-all 1 which, as the name implies, is designed to catch all of the dirt and other foreign matter which might fall through the grating 2 of the hot air or ventilating pipe 3. The invention is adapted more particularly for use on such pipes as 65 discharge the hot air into a room through the floor.

According to such systems a register 4 is used for the purpose of regulating the influx of the air. Sweepings and other dirt finding its way into the register 4 usually accumulates along the pipe 3 and establishes a very unsanitary condition. Instead of allowing such dirt to find its way directly into the pipe 3, the hopper 1 is provided to 75 intercept the dirt and make it easy to remove it when required. The pipe 3 is thus kept in a clean and sanitary condition.

The sides 5 and rear wall 6 of the hopper 1 taper to a relatively narrow chamber 7 80 (Fig. 5) in which all of the dirt accumulates due to the shape of the walls. The remaining wall 8 is straight and utilized for the mounting at 9 of a door 10 which can be raised either by means of the cable 11 in 85 Figs. 1 and 2 or the chain 12 in Figs. 6 and 7.

In the former instance the cable is provided with a ring 13 which is adapted to be hung on any of a plurality of hooks 14 in the wall adjacent to the register, this arrangement being for the purpose of adjusting the amount of opening of the door 10 in places where the hopper is utilized as a fresh air intake. The reader can readily conceive that the use of the hopper is not confined to 95 catching accumulations of dirt. Situations may arise where the furnace furnishes too much heat to the room. By simply raising the door 10 slightly, enough cold air may be admitted to temper the hot air to a comfortable degree, the hooks 14 serving as adjusting means for varying the amount of opening of the door. The cable 11 is run over one or more pulleys 15.

A spring 16, coiled about the bearing pin 105 9 of the door 10 serves to keep the door closed in place over the mouthpiece 17. The mouthpiece includes a semi-circular flange

18 which as shown in Figs. 1 and 4, surrounds a portion of the lower end of the chamber 7, not only to enable mounting the mouthpiece to better advantage but also to 5 aid in supporting the load on the hopper. The hopper includes a flange 19 at the top which is useful in applying the hopper over the opening 20 in the pipe 3. A number of bolts 21 are used in fastening the 10 hopper to the pipe, and in practice, the whole will be covered with asbestos or other insulating material, for the purpose of excluding cold air and checking the radiation of heat from the pipe 3. It is to be 15 observed that the general shape of the sides 5 and the back 6 tends to move any material which might fall into the hopper toward the opening 22 in the remaining straight wall 8. This particular arrangement insures 20 the discharge of all accumulations from the hopper when the door 10 is opened from the floor above. A slight modification in the means of opening the door and holding it to its adjusted position is disclosed in 25 Figs. 6 and 7 wherein a floor plate 23 is made use of. This floor plate has an opening 24 shaped very much like a keyhole in that the opening has a circular portion and also a narrow slotted portion. The circular portion 30 permits the free movement of the chain 12 and adjustments are made by simply sliding any one of the links into the narrow portion sidewise, the link next above furnishing a stop which holds the door in any position in which it may be at that time. A collar 25 extends through 35 the floor and provides a smooth, unobstructed passage for the chain. Although the drawing illustrates a round pipe 3 which is 40 described as a hot air pipe, it is to be understood that the principle of the invention is applicable to pipes for other purposes, for example, ventilating and cold air pipes, and may be of other shapes, for example, square, 45 hexagonal, oval, etc.

While the construction and arrangement of the improved catch-all or hopper as herein described and claimed, is that of a generally preferred form, obviously modifications and changes may be made without departing from the spirit of the invention or the scope of the claims.

I claim:

1. In combination with a pipe discharg-

ing into a register, a hopper arranged to 55 catch foreign matter falling through the register and so prevent the clogging of the pipes, a door closing an opening in the lower extremity of said hopper, and means embodied in the shape of the hopper causing 60 said matter to accumulate adjacent to the door.

2. In combination with a pipe discharging into a register, a hopper arranged to 65 catch foreign matter falling through the register and so prevent the clogging of the pipes, a door closing an opening at one side of the lower extremity of said hopper, means embodied in the shape of the hopper causing 70 said matter to accumulate adjacent to the door, and means to actuate the door from a floor above.

3. In combination with the hot air pipe 75 of a furnace discharging into a register, a hopper affixed over an opening in said pipe to accumulate foreign matter falling through 80 the register, a door at one extremity of the hopper, and means to either actuate the door from a distance to discharge said material or open the door to various predetermined distances to admit cold air into said pipe.

4. A hopper to be affixed over an opening 85 in a hot air pipe which discharges into a register, said hopper comprising a perpendicular front wall with a side opening, side and rear walls tapering downwardly to a comparatively narrow chamber to thereby accumulate foreign material behind said opening, a door closing the opening and 90 retaining said foreign material, and means to actuate the door to enable the discharge of said material.

5. A hopper for the purpose described 95 having a perpendicular front wall with a side opening, side and rear walls tapering toward said opening to form a substantially narrow chamber therebehind, a mouthpiece fixed to the front wall over said opening including a semi-circular flange extending 100 beneath said chamber to strengthen the construction, a door hinged on said mouthpiece, a spring to keep the door closed, and means to actuate the door from a distance, including means by which said actuating 105 means can be adjusted and in turn vary the amount of opening of said door.

CHARLES DWEIGHT McCALL.
